BY Victor J. Evans

ATTORNEY

P. Hickey.

WITNESS:

UNITED STATES PATENT OFFICE.

ALBERT H. KOEPP, OF SAN DIEGO, CALIFORNIA.

FINGER-NAIL SHEARS.

Application filed July 12, 1928. Serial No. 292,053.

My present invention has reference to a manicure device in the nature of a combination finger nail cutting shears, file and edge nail smoothing device of an extremely simple, 5 cheaply constructed, neatly appearing and small size that will permit of the same being readily carried in the pocket or hand bag of the user.

To the attainment of the foregoing the invention consists in the improvement as hereinafter described and definitely claimed.

In the drawings:

Figure 1 is a perspective view of my improvement.

15 Figure 2 is an approximately central longitudinal sectional view therethrough.

Figure 3 is a transverse sectional view approximately on the line 3—3 of Figure 2.

While the body of my improvement may 20 be constructed of any desired material, the same is preferably, and as disclosed by the drawings formed from a single sheet of rectangular metal which is centrally bent or rounded upon itself to provide parallel sides 25 1—1. These sides at the open end of the improvement are held spaced and are likewise reinforced by a block 2. The block is centrally formed with a groove 3 and the inner wall provided by this groove may be slightly 30 roughened, the said groove serving as a means for evening the edges of cut finger nails.

One or both sides or faces of the casing or receptacle is approximately centrally formed with a longitudinal opening 3 of a size to permit of the passage of a finger nail therethrough. Pivotal secured, as at 4—5, between the sides 1 there are disc cutter wheels 6 and 7, respectively, the peripheries of which being disposed to bridge the opening or openings 3. It is to be understood that the sides of the casing are closely related, so that a person inserting his finger nail through the

opening 3 and imparting a longitudinal movement to the device, will have his nail severed. Obviously the operator must manipulate his finger in the proper cutting of his nail.

The casing, adjacent to the bottom and at the center thereof is formed with an inwardly concaved portion 8, and directly thereabove there is journaled in the casing any desired number of burnishing wheels 9. The roughened or serrated faces of these wheels are in mesh with each other so that the turning of one wheel will impart a like turning 55 to the remaining wheel. The user of this device, after his finger nails are cut employs the burnishing wheels for burnishing his nails, and as previously stated, the wall provided by the groove 3 in the block 2 removes 60 all irregularities in the edges of the cut nails.

The simplicity of the construction and the advantages thereof will, it is thought, be perfectly apparent to those skilled in the art without further detailed description, but obviously I do not wish to be restricted to the precise details herein set forth and, therefore, hold myself entitled to make such changes therefrom as fairly fall within the scope of what I claim.

Having described the invention, I claim:

In a device for the purpose set forth, a plate which is centrally bent upon itself to provide two spaced sides, spacer elements between the sides and secured thereto, each of 75 said sides having a central longitudinal slot therethrough, a pair of cutter wheels having lapping edges journaled on shafts that are fixed to the sides and the lapping edges of the said wheels being disposed in a line with 80 the openings in the sides.

In testimony whereof I affix my signature.

ALBERT H. KOEPP.
